[57] CLAIM

The ornamental design for a container for dispensing liquid detergent or similar article, as shown and described.

DESCRIPTION

FIG. 1 is a front elevational view of a container for dispensing liquid detergent or similar article showing our new design;

FIG. 2 is a rear elevational view thereof, wherein the right and left side elevational views are identical therewith;

FIG. 3 is a top plan view thereof; and

FIG. 4 is a bottom plan view thereof.

FIG. 1

FIG. 2

FIG. 3

FIG. 4
